UNITED STATES PATENT OFFICE.

ALBERT F. STAPLES, OF CANISTEO, NEW YORK, ASSIGNOR TO SUPERIOR REGISTER COMPANY, OF CANISTEO, NEW YORK, A CORPORATION OF NEW YORK.

ACCOUNT-REGISTER.

1,022,007.

Specification of Letters Patent.

Patented Apr. 2, 1912.

Application filed June 8, 1911. Serial No. 632,092.

To all whom it may concern:

Be it known that I, ALBERT F. STAPLES, a citizen of the United States, and resident of Canisteo, in the county of Steuben and 5 State of New York, have invented certain new and useful Improvements in Account-Registers, of which the following is a specification.

This invention relates to account-registers of the type in which a plurality of bill-holder frames are pivotally mounted at the bottom, so that they may be turned like the leaves of a book. In devices of this kind it is common to make provision for the removal of the frames from the cabinet or support in or upon which they are mounted when in use, so that the frames may be conveniently transported, or stored in a safe, when not in use. Such arrangements have 10 heretofore involved the use of means permanently connecting the frames together even when so removed from the cabinet or support, said means comprising usually a portion of the means by which the frames are 15 supported or relatively positioned when in use.

The object of the present invention is to produce an arrangement in which the bill-holder frames are provided in themselves 20 with means for securing them together when not in use, these means being so constructed and arranged, however, that they do not secure the frames permanently together, so that the frames may be readily detached 25 from one another when necessary or desirable. This novel arrangement is particularly applicable to account-registers of the type in which the pivotal points of the bill-holder frames are arranged in an inclined 30 plane when the frames are in use, as it permits the frames to be locked together in the process of their removal from the cabinet or support by a sliding movement of the frames, or a relative movement of the 35 frames in their respective planes, this movement serving at once to bring the frames into the most compact position with their edges in alinement, and to secure operative engagement between the retaining-devices on 40 the adjacent frames.

Other objects of the invention, and the features of construction by which they are attained, will be set forth in connection with

the following description of the illustrated embodiment of the invention. 55

In the accompanying drawings:—Figure 1 is a side-elevation of an account-register embodying the present invention, with the near side of the cabinet removed to show the interior mechanism; Fig. 2 is a side elevation, on a larger scale, of the lower portion of several of the bill-holder frames, showing them in normal upright position; Fig. 3 is a section on the line 3—3 in Fig. 2; Fig. 4 is a partial front-elevation of the account-register of Fig. 1 on a larger scale, and in section on the line 4—4 in Fig. 1; and Fig. 5 is a side-elevation of the bill-holder frames as secured together and removed from the cabinet. 70

In the illustrated embodiment of the invention each of the bill-holder frames comprises, as is common in such devices, a sheet-metal plate or body 6 which is stiffened vertically and divided into compartments by 75 ribs 8 secured to the front and the back of the body. Between these ribs bill-holder clips 7, of any ordinary or suitable form, are mounted upon the body 6 in the usual manner. The lower margin of the body-por- 80 tion 6 of the bill-holder frames is rolled upon a wire which projects, at each end, beyond the lateral edge of the frame, so as to constitute pivots 9 for the frame. 85

The bill-holder frames just described are pivotally supported within a cabinet of ordinary form, comprising a base portion 10, a vertical back 11, and side-members 12. At the inner surface of each side-member is an inclined support 13 fixed to the cabinet by 90 screws 14. This support is provided with a series of notches, as shown in Figs. 1 and 4, adapted to receive the pivots 9 of the bill-holder frames so as to hold them in an inclined plane. When the frames are so supported they may either stand in upright position, or be swung forwardly and downwardly to substantially horizontal position 95 as shown in the case of the foremost two frames in Figs. 1 and 4. 100

To prevent the accidental disengagement of the pivots 9 from the supports 13 when the account-register is in use, I provide locking-arms 15, of which one cooperates with each support 13. Each locking-arm is pivoted at its forward end upon a screw 16, and

in order to rigidly retain the screw in proper relative position to the corresponding support 13 the latter is provided with an offset lower extremity 17 through which the screw 5 passes. When the locking-bar is in the position of Figs. 1 and 4 it engages the pivots 9 and prevents them from rising out of the notches in the support. The locking-bar is normally retained in this position by means 10 of a beveled lug 19 fixed to the inner surface of the side-member 12 of the cabinet. This lug engages the locking-bar as shown in Fig. 1, and prevents it from swinging forward. When it is desired to release the 15 frames, however, this may be done by means of a knob 18 at the upper end of the locking-bar. The resiliency of the bar permits it to be sprung inwardly sufficiently to pass the lug 19, and the locking-bar may then 20 be swung forwardly. Prior to operating the locking-bar in this manner it is necessary to swing all of the bill-holder frames to horizontal position in order that access may be had to the knob 18.

25 In removing the bill-holder frames from the cabinet they are first swung to horizontal position, as just described, and the locking-bars are swung forward to release the pivots. In order that the bill-holder 30 frames may then be drawn forward upon each other into alining position the pivots 9 must first be raised from the notches in the supports, and some resistance is 35 opposed to this operation owing to the upward inclination of the notches. To facilitate the removal of the pivots the locking-arms are arranged to perform the function of raising the pivots from the notches. To this end each locking-arm is formed at its lower 40 end with a cam-shaped portion 20 which engages the corresponding pivot of the lowermost bill-holder frame. When the locking-arm is swung forwardly, as above described, the cam-shaped portion is rotated 45 and acts to raise the pivot engaged thereby from its notch. Since the frames all rest in contact with each other at this time, this upward movement is transmitted to all of the superposed frames, so that their pivots 50 also are raised from the notches, and accordingly the frames are all free to be drawn forwardly out of the cabinet.

The body-portions of the frames are stiffened at their lateral edges, as is common in 55 such devices, and in the present instance the stiffening means are made integral also with means formed to constitute bearings between the adjacent frames as well as devices for securing the frames together when removed from the cabinet. As shown particularly in Figs. 2 and 3, each frame has at 60 each lateral margin two metal ribs 21 and 22 in the form of angle-irons, applied to the front and the rear, respectively, of the 65 body-portion and fixed by any suitable

means, such as rivets. Between the tops and the bottoms of the frames these angle-irons are cut away or reduced in width so as to leave only sufficient material to impart the necessary stiffness to the frames. At the 70 tops of the frames, however, they are left of full width so as to produce forward and rearward projections or chafing-pieces 23 and 24 which constitute bearings between the adjacent frames, as shown in Fig. 1. At 75 the bottoms also of the frames the angle-irons are left of full width so as to produce forward and rearward projections 33 and 34, respectively, constituting bearings between the bottoms of the frames. Owing to 80 the interengagement of these forward and rearward projections the frames, while normally free to have a relative sliding movement against each other, are closely confined against relative lateral movement and are 85 held positively in lateral alinement when removed from the cabinet.

To hold the frames together at the bottom when removed from the cabinet I employ 90 devices which are embodied in, or connected with, the projections 33 and 34, and which are adapted to be moved into coöperative engagement by the relative sliding movement by which the frames are removed from the cabinet. To this end each member 33 is 95 provided with a laterally-projecting stud 25, while each member 34 is provided with a slot 26, thus giving the member the form of a hook. As shown in Fig. 1, in the case of the two frames illustrated as in horizontal 100 position, the studs 25 and the hooks are substantially on the same level when the frames are in horizontal position. Accordingly, when the frames are drawn forwardly upon each other, after having been disengaged from the support 13, the several studs engage the respective hooks. In this manner the relative sliding movement of the frames is arrested at the moment when the frames are all in exactly superposed position, that 110 is, with what are normally their upper and lower edges in alinement. At the same time the studs and hooks act to prevent separation of the frames by movement transverse to the planes of the frames. After the 115 frames have been interlocked at the bottom, as just described, it is necessary to secure them both against separating movement at the top and against relative sliding movement in a direction to disengage the studs 120 from the hooks. To this end the rearmost frame is provided, at each lateral edge, with a clip 27 of sheet-metal pivoted thereon by means of a screw 28. The free end of the clip 27 has the form of a hook or lug 29. 125 Normally the clip lies in the position of Fig. 1 with the extremity 29 in engagement with the back of the rearmost frame, but when the clip is to be used it is swung forwardly to the position of Fig. 5 and may 130

then be resiliently engaged with the upper extremity of a bar 30 on the foremost frame. Owing to the inclined position thus assumed by the clip it acts both to prevent separation 5 of the tops of the frames and to prevent relative sliding movement by which the studs may be disengaged from the hooks. The frames are now securely fastened together, so that they may be transported or stored 10 apart from the cabinet. Obviously, however, by disengaging the clips 27 the frames may be separated, if desirable, so as to be stored in any convenient numbers in such spaces as may be available in a safe or other 15 place of deposit. To replace the frames in the cabinet they are laid in horizontal position thereon with the pivots of the foremost frame resting upon the cam-portions 20 of the locking-arms, and the clips 27 are then moved to inoperative position. The locking-arms are then swung rearwardly, and since they engage the pivots from in front their movement is imparted to the latter so as to cause the frames to have a 25 rearward sliding movement by which the pivots are moved into engagement with the notches in the supports 13. By this same movement the studs 25 are disengaged from the slots 26, and the frames may then be 30 swung to normal upright position.

While the studs and hooks coöperate as above described when the frames are in horizontal position, it will be apparent that they will not engage each other when the 35 frames, during the use of the account-register, are being swung upwardly or downwardly in any number. This is due to the fact that the linear distance between the pivotal axes of the adjacent frames is greater 40 than the distance between these pivots when the frames are in the position of Fig. 5, so that the studs swing clear of the outer extremities of the hooks instead of engaging the hooks at this time.

45 As the foremost and rearmost frames require no interlocking devices on their front and rear surfaces, respectively, these frames may be provided at their lateral edges with solid bars 30 and 32 respectively. To prevent the frames from slamming when they are swung forwardly and downwardly, buffers 31 of rubber, or other suitable material, are mounted on the base of the cabinet in position to be engaged by the bars 30.

55 My invention is not limited to the embodiment thereof hereinbefore described and illustrated in the accompanying drawings, but may be embodied in various other forms within the nature of the invention as it is 60 defined in the following claims.

I claim:—

1. An account-register having, in combination, a plurality of bill-holder frames provided with interlocking devices to secure the 65 frames together, said devices being movable

into coöperative position by relative movements of the frames in their respective planes, and means for pivotally supporting the frames in relative positions in which the locking devices are normally out of operation. 70

2. An account-register having, in combination, a plurality of bill-holder frames provided with interlocking devices to secure the frames together, said devices being movable 75 into coöperative position by relative movements of the frames in their respective planes, and means for pivotally supporting the frames at the bottom with their pivotal axes arranged in an inclined plane. 80

3. An account-register having, in combination, a plurality of bill-holder frames provided with interlocking devices to secure the frames together at the bottom, said devices being movable into coöperative position 85 by relative movements of the frames in their respective planes, and means for pivotally supporting the frames at the bottom with their pivotal axes arranged in an inclined plane. 90

4. An account-register having, in combination, a plurality of bill-holder frames provided, near the bottom, with interlocking devices, said devices comprising a hook on each frame and an abutment on the next adjacent 95 frame adapted to be engaged with said hook by a relative movement of the two frames in their respective planes, and means for pivotally supporting the frames at the bottom with their pivotal axes arranged in an inclined plane. 100

5. An account-register having, in combination, a plurality of bill-holder frames provided with interengageable devices by which relative sliding movement of the frame is 105 limited in one direction to retain the frames in position with their upper and lower edges in substantial alinement, means for detachably connecting the frames together when not in use, said means being adapted both 110 to prevent separation of the frames and to prevent relative sliding movement to disengage said devices, and means for pivotally supporting the frames in relative positions in which said devices are normally out of 115 operation engagement.

6. An account-register having, in combination, a plurality of bill-holder frames provided at the bottom with pivots, a support for the frames provided with upwardly-opening recesses to receive said pivots, and means for raising one or more of the pivots to disengage them from the recesses and facilitate the removal of the frames from the support. 120

7. An account-register having, in combination, a plurality of bill-holder frames provided at the bottom with pivots, a support for the frames provided with recesses to receive said pivots, and unitary means for 130

locking the pivots in the recesses when the account-register is in use, and for expelling the pivots from the recesses when the bill-holder frames are to be removed from the support.

8. An account-register having, in combination, a plurality of bill-holder frames provided with interengageable devices to prevent relative lateral sliding movements of the frames, the frames being also provided at the bottom with laterally-projecting pivots, two inclined supports provided with recesses to receive said pivots, means for securing the frames together in alining position when removed from the supports, and means for engaging the pivots and producing a relative sliding movement of the frames to engage the pivots with said recesses when the frames are applied to the supports.

9. An account-register having, in combination, a plurality of bill-holder frames, each frame being provided at its lateral edges with oppositely-disposed forwardly and rearwardly-projecting angle-irons, one of said angle-irons having its rear-portion formed to constitute a hook near the bottom of the frame, and the other angle-iron at the same edge of the frame being provided with an abutment adapted to engage the hook on the next adjacent frame, and means for pivotally supporting the frames at the

bottom with their pivotal axes separated by a distance sufficient to permit the abutments to clear the hooks when the frames are 35 swung about said axes.

10. An account-register having, in combination, a plurality of bill-holder frames provided with coöperating abutments to limit relative sliding movements of the frames and hold the frames in alinement when not in use, means for securing the frames together and retaining said abutments in co-operative relation, and means for pivotally supporting the frames, when in use, in relative positions in which the frames are free to be swung about their pivotal axes.

11. An account-register having, in combination, a plurality of bill-holder frames provided with pivots at the bottom, an inclined support provided with recesses to receive said pivots, and an arm pivoted adjacent the lower end of said support, the arm having a portion formed to engage the pivots and lock them in the recesses, and another portion formed to engage one or more of the pivots and to expel them from the recesses when the arm is swung out of locking position.

ALBERT F. STAPLES.
